UNITED STATES PATENT OFFICE

KORNELIUS QUIRING, OF OAKLAND, CALIFORNIA

COLLAPSIBLE DRAWING TABLE

Application filed June 12, 1929. Serial No. 370,447.

The invention relates to a collapsible table particularly designed for use in the drawing arts.

An object of the invention is to provide an improved table structure of the class described providing for both angular and height adjustments of the drawing board thereof.

Another object of the invention is to provide a table of the class described with auxiliary shelves and supports whereby to facilitate and amplify its use.

A further object is to provide drawer means in the structure.

Yet another object of the invention is to so mount and relate the various elements of the structure that it may be folded as a unit to provide a particularly compact assembly.

A more specific object of the invention is to provide an improved adjustable and collapsible frame for mounting a drawing board and the like.

A more general object of the invention is to bring about a new combination and correlation of parts in a device of the class described whereby marked economies in manufacture will be effected and the efficiency of the use of the device will be enhanced.

The invention possesses other objects and features of advantage, some of which, with the foregoing, will be set forth or be apparent in the following description of a preferred form of the invention which is illustrated in the accompanying drawings, in which:

Figure 1 is a front elevation of a table embodying the invention and in set-up position, portions of the structure being broken away to disclose certain details thereof.

Figure 2 is a side section at 2-2 in Figure 1.

Figure 3 is a side elevation of the table in folded condition.

Figure 4 is an enlarged face view of a portion of the structure shown in Figure 3.

Figure 5 is a plan section at 5-5 in Figure 4.

Figure 6 is a section at 6-6 in Figure 5.

Figure 7 is an enlarged face view of a portion of the showing of Figure 2.

Figure 8 is a plan view at 8-8 in Figure 7.

Figure 9 is an enlarged fragmentary elevation of a shelf hinge and its mounting taken at 9-9 in Figure 1, a hinge leaf being shown detached.

Figure 10 is an elevation taken at 10-10 in Figure 9.

Figure 11 is an enlarged fragmentary section at 11-11 in Figure 1.

Figure 12 is an underneath fragmentary perspective view of an auxiliary board for mounting on the table, attaching means for the board also being shown.

Figure 13 is an end elevation of the table, and shows the auxiliary board of Figure 12 mounted thereon.

Figure 14 is an enlarged fragmentary section at 14-14 in Figure 13.

Figure 15 is an enlarged fragmentary section at 15-15 in Figure 13.

As herewith particularly disclosed, the invention is seen to be incorporated in and with the structure of a drawing table 16. Laterally spaced side members 17 and 18 connected by cross members 19, 20 and 21, cooperate to provide an integral back unit 22 of the table frame, with the lower ends of the members 17 and 18 constituting the back table legs. Similar brackets 23 and 24 are mounted on the upper portions of the side members 17 and 18 respectively, said brackets extending forwardly from the back unit 22.

Leg members 25 and 25' are pivoted to the brackets 23 and 24 respectively by means of hinges 26, and link bars 27 connect intermediate points of the legs 25 and 25' with lower points of the frame members 17 and 18 respectively. As shown, the link bars 27 are pivotally secured to the legs and frame members by means of hinges 28 and 29 respectively. Casters 30 are preferably provided on the lower ends of the legs 25 and 25' for engagement along a surface supporting the table; as shown, the casters 30 are of the roller type with their axes of rotation parallel to the plane of the back unit 22. A tie member 31 connects the legs 25 and 25' adjacent their free ends whereby the legs are arranged to cooperatively define a plane and to

55

60

70

75

80

85

90

95

100

be at all times similarly disposed with respect to the unit 22.

It will now be noted that the brackets 23 and 24 are movable along the side members 17 and 18 of the back frame unit 22 whereby, through the action of the links 27, the angular relation of the legs 25 and 26 to the unit 22 may be adjustably and positively controlled. Means are provided for retaining the brackets 23 and 24 for movement in fixed paths along the members 17 and 18, and for fixing said brackets in adjusted position, the structure shown being hereinafter described in detail. The back frame unit 22 is preferably arranged to retain a fixed angular relation to a plane supporting surface when the present table structure is set up thereon, and in the present instance is arranged to be and remain perpendicular to such a supporting surface as the legs 25 and 25' are variously disposed. For satisfying the latter condition, the linkage provided by the links 27 is such that the floor engaging portions of the casters are confined to movement in a plane extending forwardly from the foot of the back frame unit 22 and perpendicular to the plane thereof. In this manner, the legs 25 and 25' may be disposed parallel to and against the members 17 and 18 respectively, as shown in Figure 3 wherein the table is disclosed in folded-up condition, or extended as shown in Figures 2 and 13, it being noted that the legs 25 and 25' function as supporting elements of the table structure in a relatively large range of angular positions thereof. For bringing out the foregoing relation, a second extended position of the legs and associated elements is indicated in dotted lines in Figure 2.

10 The folding frame now described is arranged for the support of a table top, or board, 32 in angularly adjusted position. The back edge of the top 32 is hingedly related to and carried by the brackets 23 and 24 by means of hinges 33 secured to the top and said brackets. Support of the top 32 at the front thereof is provided by means of struts 34 hinged to the front portion of the top and at opposite sides thereof and having the lower ends thereof arranged for a footing on the legs 25 and 25'. As shown, the struts 34 are arranged for swinging about aligned axes in planes just inside of the planes of movement of the legs and parallel thereto, and are provided with pins 35 extending laterally therefrom for engaging a selected one of notches or recesses 36 provided along the forward leg edges. A tie member 37 secures the struts 34 together whereby they define a plane parallel to their axis of hinging, said tie member being somewhat above the free strut extremities to leave leg room therebeneath.

15 It will now be clear that two adjustments are provided for the top 32, namely, the

general height adjustment provided through varying the elevations of the brackets 23 and 24, and the slope adjustment made possible through the engagement of the free ends of the struts 34 in different of the recesses 36, such adjustability of the top 32 being an important element of the present invention. The pivotal axis of the top 32 with respect to the brackets is seen to lie at or below the bottom face of the top whereby the latter may be folded flat against the upper ends of the legs 25 and 26 while the struts 34 are extended upwardly and between the said legs. In this manner, the top is arranged to be folded into parallel relation with the legs and back unit without requiring its dismounting.

As particularly shown, the recesses 36 comprise the notches of metallic rack bar members 38 fixed to the outer edges of the legs 25 and 25', and the lower ends of the members 38 are seen to provide brackets 39 to and between which a foot rail 41 is secured for the use of a person using the table. In the present embodiment, the top and the various leg, strut and tie elements hereinbefore described are arranged to be formed of wood, but it will be obvious that some or all of the same might be made of metal without departing from the spirit of the present invention.

100 The brackets 23 and 24 are of similar and complementary structure for mounting on the back frame members 17 and 18 respectively. By particular reference to Figures 4 to 8 inclusive, each of said brackets is seen to comprise a generally triangular plate 42 for disposal in a plane perpendicular to that of the back frame unit 22, said plate having perpendicularly related top and rear edges. A flange is provided peripherally about the plate, said flange extending transversely of the plate and, in the present instance, inwardly of the adjacent table side edge. A slide block 44 is provided at and along the vertical flange portion 45, said block being provided with a groove 46 opening from the rearward side of the block, the groove being rectangularly widened at its bottom. Flat bars 47 are fixed to and along the back frame members 17 and 18 in spaced relation therefrom and in mutually parallel relation, said bars being slidably engageable in the wider bottom portions of the grooves 46 of the opposed blocks 44 whereby a lateral separation of the blocks and bars is prevented and relative longitudinal sliding of the engaged blocks and bars is permitted. In the present instance, the bars 47 are seen to be mounted on spacer posts 50 fixed to the members 17 and 18 whereby the weight of the parts is minimized. It is noted that the blocks 44 form parts of bracket structures which may properly be termed slides or slide brackets.

110 Means are provided for disposing and securing the slide brackets 23 and 24 in cor-

130

responding adjusted positions. As shown, a shaft 48 is journaled through and between the slide plates 42, said shaft being provided with a hand crank 49 at one end thereof and carrying like pinions 51 fixed thereto at points opposite the slide grooves 46. The outer faces of the bars 47 are formed to provide racks 52, and the blocks 44 and bracket flange portions 45 are in each case perforated between said 10 rack and the opposed pinion 51 whereby the pinions are arranged to engage the racks. In this manner, a turning of the crank 49 to rotate the shaft 48 is arranged to simultaneously raise or lower the slides in like amount 15 for adjusting the height of the back edge of the supported top board 32 or a complete raising for effecting a folding up of the table.

The leg hinges 26 and board hinges 33 are seen to have the fixed leaves thereof secured to 20 and against the obliquely disposed forward flange portion 53 of the plate 42 at appropriate points thereof. The top flange portions 54 of the plates 42 are arranged to cooperatively support a shelf member 55 mounted thereon 25 and preferably extend from the rearward edge of the board 32 to the back plane of the unit 22. For supporting the rear edge of the shelf 55, the flanges 54 are seen to be extended rearwardly along the inner sides of the support members 17 and 18 and the extensions thereof are reinforced by means of a vertical web 56 integrally connecting their outer edges with the inner edges of the vertical flange portions 45. The shelf 55 is designed for supporting tools, ink, and the like and is preferably provided with upwardly extending flanges 57 and 58 at the front and rear thereof for retaining such articles thereon, the shelf thus constituting a shallow trough. It is 40 noted that the flange 57 is particularly important as a means for keeping articles from the shelf out of the V-shaped groove defined between the top and shelf at their abutment.

Brackets 61 extend upwardly from the top 45 ends of the members 17 and 18 and carry between them a pane 62 of transparent glass or the like. Preferably, and as shown, the lower edge of the pane 62 registers with the top of the upper back frame tie member 19, said 50 member being grooved slightly to receive the pane, and being provided at its forward top portion with a pencil groove 63. The pane 62 slopes backwardly from the groove of the member 19 and is seen to provide, either alone 55 or in cooperation with the grooves of the tie member 19, a convenient mounting for sketches and transparent celluloid triangles and curves, yet offers no shadow on the board when interposed between the board and the 60 light.

In the use of drawing tables of the type described, more table and storage space is frequently needed than is supplied by the table top. Accordingly, and as shown in Figures 65 1, 2, 3 and 13, I provide the present structure

with added shelf space to more than double the area of support provided by the top 32 and shelf 55. As particularly shown, said additional shelf space is provided by upper and lower shelves 64 and 65 displaceably supported from the back frame unit 22 and beneath the top 32. The shelf 65 extends between the back frame members 17 and 18 and is hinged to the lower tie member 21 by means of hinges 66 whereby it is arranged for 70 swinging between a horizontal and forwardly extended position upwardly to an upright position entirely between the members 17 and 18. Support for the outer end of the shelf 65 is provided by chains 67 extending therefrom 80 to points on the members 17 and 18 above the points thereof to which the shelf extends when in said upright position.

The upper shelf 64 is seen to also swing between the members 17 and 18 as well as between the legs 25 and 26 and between the bars 27. Hinges 68 connect the rear part of the shelf 64 with the inner sides of the members 17 and 18, and the shelf 64 is arranged to be swung downwardly to lie between and 90 forwardly of the members 17 and 18, and forwardly of the shelf 65, when the table is folded. Support of the forward edge of the shelf 64 is afforded by means of struts 71 hinged thereto and engaging on the front portion of the shelf 65. Preferably the lower strut ends and shelf are provided with cooperating pin-and-socket connections for preventing a lateral displacement of the strut bottom, this structure being disclosed in detail in Figure 11 wherein pins 72 and sockets 73 are shown as provided respectively on and in the shelf 65 and struts. The hinges 74 of the struts 71 are preferably of the triple-leaf type and are so connected between the shelf 100 and struts as to permit a slight lifting of the shelf without releasing the other strut ends from their engagement with the shelf 65, such being indicated in Figure 13. When the table is folded, the struts 71 are arranged 105 to lie between the shelves 64 and 65.

Referring now to the structure of each of the hinges 68, the details of which are disclosed in Figures 9 and 10, it is seen that one leaf 74 thereof is flat and arranged to be 110 mounted on the under side of the shelf 64 with its knuckle portions directed rearwardly. The other leaves 75 of the hinge 68 are bracket-like in structure and include a flat plate portion 76 fixed against the inner sides 115 of the members 17 and 18. Flanges 77 and 78 extend transversely from the top and front edges of the plate and inwardly of the members 17 and 18, said flanges being formed to provide horizontally disposed knuckles for 120 securing to the knuckles of the leaves 74 by the application of a usual pintle. It is noted that the hinge axis defined by the hinges 68 is somewhat forward of the front plane of the members 17 and 18, such being necessary 125

to permit the aforesaid folded disposal of the shelf 64. It is further seen that the hinge plates 76 have perforated bosses 79 extending therefrom to provide anchors for the upper ends of the chains 67.

A sliding drawer 80 is mounted on and beneath the shelf 64, said drawer being seen to fit between the hinges 68 and to be slidably supported on and between parallel depending plates 81 fixed beneath the shelf. As shown in Figure 1, the plates 81 are provided with tongues slidably engaging complementary grooves provided in the opposed side members 82 of the drawer. It is noted that the provision of the drawer 80 beneath the shelf increases the required forward extension of the hinge leaves 75 by the depth of the drawer.

It will now be noted that the top 32 comprises a plate member 85 mounted on and between side edge rails 86, said plate being flush with the said rails at its edges thereat. The hinges at the front and rear of the board are seen to be secured to the lower edges of the rails 86. A cleat 87 is preferably provided across the front edge of the plate 85 for retaining removable drawing boards and the like on the board when the latter slopes. The now-described structure of the top 32 is a preferred, though not essential one, and the rails 86 are further utilized in a manner to now be described.

As is well known, artists frequently have need of a vertical, or substantially vertical, working surface. While the desired disposal of the top 32 may be approached somewhat with the structure hereinbefore described, means are preferably included with the present structure to provide a truly vertical working surface when and as required. Referring particularly to Figures 12 to 15 inclusive, it is seen that the aforesaid means comprises an auxiliary board 88 and means for mounting the same on the top 32. Adjacent and about midway of the side edges of the board 88, said board is provided with a pair of hinge leaves 89 having coaxially related knuckles or eyes. The hinge leaves 89 are fixed beneath the board 88, and the eyes thereof are arranged for coaxial engagement with the eyes of hinge leaves 93, the latter being of a special structure.

Transverse sockets or holes 94 are provided in the rails 86 adjacent the front ends thereof, the axes of said sockets being parallel to the plane of the top 32. The leaves 93 are seen to comprise two perpendicularly and integrally related flat portions 95 and 96, with the leaf portions 95 providing the necessary hinge eyes and arranged to overlie the upper top face at opposite side edges thereof. Projections or bosses 97 extend transversely from the leaf portions 96 at the same side thereof as do the portions 95, and said bosses are arranged to engage the sockets 94 when the

portions 95 bear on the top surface of the board, it being clear that this mounting of the leaves 93 engages the portions 96 against the side edges of the rails 86. With the two hinge leaves 93 thus mounted, the eyes of co-operating hinge leaves 89 and 93 are arranged for registration whereby hinge pins 98 may be inserted through the aligned eyes for pinning them together. Since the board 88 is an auxiliary attachment for the table, the pins 98 are not fixed in place but are removable for dismounting the board 88. When the board is dismounted, the hinge portion 93 may, of course, be removed without releasing screws or other positively acting fastening means.

Links 101 are hingedly mounted on the board 88 above the hinge leaves 89, said links being longitudinally slotted for the adjusted reception of bolts 102 therein, said bolts being mounted in the rails 86 at intermediate points thereof. As particularly shown, the bolts 102 are of the wagon-bolt type whereby they have a polygonal shank portion adjacent their heads, and said bolts are removably disposed in complementary perforations 103 through the rails 86 whereby they are held against rotation, the bolt heads being innermost. The extending portions of the bolts 102 are disposed through the slots of the links 101, and wing-nuts 104 are applied to the outer bolt ends for clamping the links between themselves and the rails 86. In this manner, the board 88 is arranged to be adjustably disposed and fixed at any desired angle, and the use of the mounting means therefore requires only the provision of the sockets 94 and perforations in the rails 86.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In a folding table, a back frame portion including upright side members, brackets adjustable on and along said side members, a top supported in part on the brackets, a leg pivoted to a said bracket, and a strut hinged to said top and adjustably engaged with said leg to support said top in position for use.
2. In a folding table, a back frame portion including upright side members, brackets adjustable on and along said side members, a top supported in part on the brackets, legs

pivoted to said brackets, and struts hinged to said top and engageable with said legs to complete the support of said top in position for the use thereof.

3. In a folding table, a back frame portion including upright side members, a cross-member securing said side members adjacent the top thereof, and a pane of transparent material mounted on said frame above said cross-member and sloping upwardly and backwardly therefrom to provide a supporting backing for relatively flat articles disposed in generally upright position thereat.

4. In a folding table, a back frame portion including upright side members, brackets adjustable on and along said side members, a top hinged to said brackets for support in part thereon, legs pivoted to said brackets, and struts pivoted to said top and removably engaged with said legs to complete the support of said top, said top and legs and struts being arranged for disposal in parallel adjacency to said side members without disconnection thereof.

5. In a folding table, a back frame portion including upright side members, brackets adjustable on and along corresponding upper portions of said side members, legs pivoted to said brackets, and links connecting said legs with points on said members below the said brackets whereby the free ends of the legs are constrained to move in a common and predetermined plane.

6. In a folding table, an upright back frame portion including upright side members, brackets vertically adjustable on and along said side members, means for disposing and securing said brackets in a plurality of adjusted positions thereon, a shelf carried horizontally by and between said brackets, a top member having the back edge thereof opposite the front edge of said shelf and hingedly carried on said brackets, and means for adjustably supporting the front edge of said top.

7. In a folding table, a back frame portion including an upright member, a bracket adjustable on and along said member, a top supported in part on the bracket, a leg pivoted to said bracket, and a strut pivotally engaging said top and releasably engaging said leg to support said top in position for use.

8. In a folding table, a back frame portion including an upright member, a bracket adjustable on and along an upper portion of said member, a leg pivoted to said bracket, and a link connecting said leg with said member below said bracket whereby the lower extremity of the leg is constrained to movement in a predetermined straight-line path as said leg is pivotally moved.

In testimony whereof, I affix my signature.
KORNELIUS QUIRING.
